UNITED STATES PATENT OFFICE.

MARCUS P. SCHENCK, OF FULTON, NEW YORK.

CIDER-MILL.

SPECIFICATION forming part of Letters Patent No. 298,362, dated February 12, 1884.

Application filed July 5, 1883. (No model.)

To all whom it may concern:

Be it known that I, MARCUS P. SCHENCK, a citizen of the United States, residing at Fulton, in the county of Oswego and State of New York, have invented certain new and useful Improvements in Cider-Mills, of which the following is a specification.

My invention relates to an improvement in the construction of cider-presses, and in the arrangement of the gearing for operating the press-beams.

It also relates to an improved chute or hopper for measuring and conducting uniform quantities of pomace to be placed in each layer, said chute being constructed in such a manner as to catch and conduct to a suitable pipe any juice which may run out of the pomace before reaching the press-board; and, further, to an improved apparatus for handling the cheeses before and after insertion into the press; and, further, to an improved safety-gearing, whereby the power which operates the press will be cut off after any desired degree of pressure has been reached, and also to details to be hereinafter described.

In order that my invention may be fully understood, I will proceed to describe it with reference to the accompanying drawings, in which—

30 Figure 1 is a vertical section of my improved press. Fig. 2 is a plan of the same. Fig. 3 is an elevation of my improved pomace-chute. Fig. 4 is a side elevation of my improved turn-table. Fig. 5 is a plan of the same, showing its adaptability to any number of presses, and the tracks for supplying it with fresh cheeses and carrying them off after they have been pressed. Fig. 6 is a perspective view of the wear-irons of the turn-table.

40 1 represents the bed of the press, through which pass four screw-threaded uprights or standards, 2, which also pass through openings in the upper press-beams, 3, and through pinions 4, having internal threads corresponding with those of the uprights 2. The standards 2 are threaded in opposite directions—that is to say, the pairs at the ends of the press are formed with right and left threads, respectively.

50 On the under sides of the pinions 4 are

shoulders or bosses 5, each having a circular groove, with which engages a lug or lip, 6, securely bolted on the top of the press-beam. When pressure is exerted, the face of the shoulder 5 bears against a metallic plate, 55 which is also bolted to the top of the beam. Motion is imparted to the pinions 4, in either direction, through the medium of a chain, 7, driven by a sprocket-wheel mounted on a swinging frame, similar to that described in my Patent No. 258,134, dated May 16, 1882, gearing with a sprocket-wheel, 8, mounted on shaft 9, carrying bevel-pinions 10 10, gearing with similar bevel-pinions 11 11, mounted on upright shafts 12 12, carrying pinions 13 13, 65 meshing with the inner peripheries of the pinions 4.

Pivoted to one end of the press-beams is a lever, 14, which rests near its center on a thumb-screw, 15, and carries at its other end 70 a friction-wheel, 16.

Mounted on the shaft 9 is a collar, 17, having flanges 18.

Around the collar 17 passes a loose belt or cord, 19, which passes up over a pulley, 20, 75 and thence to the clutch or other device for shifting the power to or from the idle-pulley. When the press has reached the desired maximum pressure, the beam 3 will bend or spring. This will cause the pulley 16 to rise and press 80 against the belt 19 on the under side of the collar 17, and the rotation of the shaft 9 will cause a pull on the said belt, which will shift the working-belt from the working to the idle pulley, thus stopping the press. Any desired degree of pressure may be reached before the stopping of the press, as above described, by adjusting the thumb-screw 15 up or down, as may be necessary. The beams 3 3 are tied together by suitable tie-rods or braces, and have 85 secured to their under sides a heavy press-board, 21.

22 represents a chute for supplying the pomace from the floor above. This chute is provided at bottom with a trap-door, 23, 95 hinged at 24, and formed around its upper edge with a ledge or rib, 25, for holding and conveying any juice which may run out of the pomace into a trough, 26, which empties into a pipe, 27, whereby it is conveyed to any de- 100

sired receptacle. This trap-door 23 is held in its closed position by the edge of the trough 26, which engages with a notch on the end of it, said trough being suspended by a spring, 5 28, of any suitable construction.

For the purpose of releasing the door, I secure a sliding rod or bar to the under side thereof, the fore end of said rod resting against a lug or projection on the under side of the 10 trough. When this rod is pushed forward, it disengages the edge of the trough from the door and permits it to drop.

A suitable distance from the bottom of the chute is a sliding cut-off, 29, having a rack, 15 30, with which gears a pinion, 31, mounted on a crank-shaft, 32. This slide is retracted until the chute has had time to fill. The supply is then cut off and the trap-door 23 released, allowing the pomace to drop onto the press- 20 board. The door 23 is then closed, the cut-off opened, and the same manipulation repeated. Thus it will be seen that the difficulty heretofore existing of putting an equal amount of pomace in the layer is, by my improved chute, 25 entirely overcome.

Suspended from the ceiling by ropes 33, passing over pulleys 34, is a flexible shield, 35, preferably made of cloth or canvas with wooden ribs, and of the shape shown, the lower portion of mouth being of less area than the press-board upon which the pomace is delivered. This device is for the purpose of preventing the pomace from spattering beyond the press-board and onto the floor, as is the case with 30 devices now in use. This shield may be held suspended by a counterbalance-weight, 35; or the rope 33 may be otherwise anchored, if desired.

The press, as above described, is very powerful and adapted to press a large quantity of cheese at each operation; and to provide for the easy and speedy insertion of a new cheese into the press, which is too heavy for manipulation by hand, and the removal of the expressed 40 one, I provide a turn-table supported and held at its center by suitable wear-irons, consisting of a metallic plate, 36, secured to the under side thereof and formed with an annular rib, which engages with a similar annular 45 depression in a similar metallic plate, 37, secured to the floor. This turn-table consists, preferably, of a rectangular frame, 38, provided at each end with wheels 39, running on a circular track or way, 40. Secured to the 50 top of the turn-table is a track, 41, for guiding a car or carriage, 42, having wheels 43. In the center of the turn-table are two corner or angle pieces—one on either side—placed the width of the racks apart, for the purpose of 55 aiding in forming the cheeses evenly. It is also provided with a latch of any suitable construction for holding the car in place.

For the purpose of catching any juice which may run out while the cheese is on the turn-table, the car or press-board is provided with 60 a marginal flange and an opening at one end

for the escape of said juice, which drips into a trough, 44, running lengthwise of the table and sloping toward the center, where it empties into a funnel, 45, having a pipe leading 70 through the wear-irons, and emptying into a suitable receptacle at any desired part of the building. The press is also provided with a track, 46, whose ends are flexible and project beyond the front and back thereof, and are supported by blocks mounted on cross-ties 47. The cross-ties are raised and lowered by means of an eccentric, 48, mounted on either end of a bar, 49, having an operating-lever, 50. When the car is being run in or out of the press, the 80 lever 50 is lowered, which raises the ends of the track flush with that on the press and table, as shown in Fig. 1. To relieve the wheels of the press-board of any load when the pressure is applied, the lever 50 is raised, thus letting 85 the ends of the track fall, and letting the bottom of the car, which forms the press-board, rest firmly on the bed of the press.

The relative positions of the chute, turn-table, and press may be such that the table can be 90 swung around under the chute, and the cheese laid up, then swung around and run into the press, and the other end loaded with a fresh cheese. By this time the one in the press will be ready for removal, which is done by running it onto the table, turning the table, and running the car with the expressed cheese off onto a track leading out of the building; or, if more than one press is used, they may be arranged as shown in the diagram, Fig. 5. In 100 this figure I have shown the table located in the center of four presses, with two branch tracks—one for supplying the fresh cheeses to the table, and another for carrying off the expressed cheeses. By this arrangement of 105 tracks the chute may be located and the cheeses laid up in another room or another part of the same room and run onto the table as needed.

Any novel subject-matter which I have described but not claimed in this application is 110 hereby reserved to be claimed in future applications.

Having thus described my invention, the following is what I claim as new therein and 115 desire to secure by Letters Patent:

1. In a cider-press, the combination, with the bed 1, stationary screws 2, moving press-beams 3, and pinions 4, of a train of driving mechanism, 8 9 10 11 12 13, located between said moving beams, substantially as set forth.

2. In a cider-press, the combination, with the vertically-moving press-beams 3, of an adjustable lever, 14, pivoted at one end to said beams, and carrying at the other end a friction-wheel, 16, and a friction-wheel, 17, mounted on the main driving-shaft, and having flanges 18, for retaining a loose belt, 19, substantially as and for the purpose set forth.

3. In a cider-mill, a pomace-chute having a hinged trap-door and a sliding cut-off above 130 said door, for measuring an equal quantity of material for each layer, as set forth.

4. In a cider-mill, a pomace-chute having a hinged trap-door provided with a marginal flange, in combination with a trough for catching the juice and delivering it into a suitable 5 pipe or conveyer, as set forth.

5. In a cider-mill, the combination, with the pomace-chute 22, having hinged door 23, of a trough, 26, suspended by a spring, and adapted to hold said door in a closed position, 10 and a suitable trigger for liberating it, as set forth.

6. In a cider-mill, the combination, with the chute 22, having trap-door 23, of a cut-off 29, operated by a crank through the medium 15 of rack 30 and pinion 31, as set forth.

7. In a cider-mill, the combination, with the pomace-chute, of a flexible shield suspended from the ceiling by ropes passing over pulleys, and having a counterbalancing-weight, 20 substantially as and for the purpose set forth.

8. In a cider-mill, a turn-table consisting of a frame supported and held centrally by suitable wear-irons, substantially as herein described, and having at its ends wheels running on a circular track or way, substantially 25 as and for the purpose set forth.

9. The combination, with a turn-table supported at each end by suitable wheels, of a pair of corrugated wear-irons adapted to work 30 together, as and for the purpose set forth.

10. The combination, with a turn-table supported at each end by suitable wheels, and having a central longitudinal trough, as de- 35

scribed, of a pair of corrugated wear-irons adapted to work together, and having a central opening, as and for the purpose set forth. 35

11. In a cider-mill, the combination, with a wheeled press-board, of a turn-table having upright corner-pieces adapted to assist in laying up the cheeses evenly, as set forth. 40

12. In a cider-mill, the combination, with a turn-table carrying a track on the top thereof, of a wheeled press-board and a suitable latch for holding it in place on the turn-table, substantially as and for the purposes set forth. 45

13. In a cider-mill, the combination, with a turn-table, of a wheeled press-board having a marginal flange and an opening in the front thereof for discharging juice into a suitable trough or receptacle, as set forth. 50

14. In a cider-mill, the combination, with a turn-table carrying tracks or ways, of a press-bed having similar tracks and a wheeled press-board, as set forth.

15. In a cider-press, the combination, with 55 a wheeled press-board, of a track secured to and having its ends project beyond the press-bed, and connected to cross-beams operated by an eccentric-lever, whereby said ends are raised or lowered, substantially as and for the 60 purposes set forth.

MARCUS P. SCHENCK.
